UNITED STATES PATENT OFFICE

STEPHEN L. WILLIAMS, OF BRIDGEPORT, OHIO, ASSIGNOR TO EXTRUDED METAL PRODUCTS COMPANY, OF BRIDGEPORT, OHIO, A CORPORATION OF OHIO

PICKLING APPARATUS

Application filed May 13, 1932. Serial No. 611,092.

This invention relates broadly to metal pickling apparatus, and is an improvement upon my prior patents numbered 1,734,986 and 1,738,412, dated, respectively, November 5 12, 1929, and December 3, 1929.

The primary object of the invention is to provide an improved mechanism designed primarily for use in the pickling of strips of rolled steel of varying widths and lengths 10 which have been rolled into coil form.

A further object of the invention is to provide a pickling apparatus in which improved means is provided for opening or spreading the convolutions or coils of such metal strips, 15 thus exposing the entire surface of said strips to the action of the pickling fluid of the bath.

A further object is to provide a pickling apparatus in which the operating mechanism is so constructed and operates in such a manner 20 that the pickling operation is effected with a minimum of power consumption.

A still further object of the invention is to provide a pickling apparatus designed primarily for the pickling of coiled metal 25 strips and wire, but which may readily be transformed into a pickling apparatus for metal sheets, forgings, bars, and the like with a minimum of effort and time, thereby affording pickling apparatus serving a dual 30 purpose.

With these and other objects in view, the invention resides in the features of construction, combinations of elements and arrangement of parts which will hereinafter be fully 35 described, reference being had to the accompanying drawings, in which—

Figure 1 is a top plan view of the invention;

Figure 2 is a side elevation of the same, 40 the pickling tank being shown in section in order to depict the strip carrier and the cradle; and—

Figure 3 is a section on line 3—3, Fig. 2.

Referring to said drawings, 1 and 2 designate 45 companion pickling tanks of rectangular form disposed in spaced parallel relation and containing the pickling fluid or bath. Located outwardly from and in spaced relation to the opposite ends of each of the tanks 50 are suitable foundations 3, each of said foun-

dations being preferably made from concrete and being of a size and shape adapted to conveniently accommodate the thereby supported mechanism.

Gear boxes 4 and 5 housing appropriate 55 gearing are permanently located on the foundations 3 above the tanks and at each of the opposite ends of said tanks, said gear boxes being located between the two adjacent side walls of the tanks 1 and 2. Appropriately 60 coupled to stub shafts 9 and 10 and protruding exteriorly of the gear boxes 4 and 5 is a longitudinally extending drive shaft 6, said shaft being disposed in parallel relation to the tanks and above the latter, and being 65 journaled intermediate its ends in a center bearing 7, said bearing receiving its support by means of an H-beam 8 which spans the space between the foundations 3 and has its opposite ends supported by the latter. 70

A pair of bearings 11 are suitably supported by the foundation 3 at each of the opposite ends of the tanks 1 and 2 and each pair of bearings has journaled therein a shaft 12.

Each of the four shafts 12 carries on its 75 outer end a crank arm 13 and carries on its inner end a crank arm 14. Short shafts 15 extend transversely from each of the gear boxes 4 and 5 and at right angles to the shafts 9 and 10, and each of the short shafts 15 80 carries a crank arm 16.

Each of the crank arms 13 has pivotally attached thereto the upper end of a connecting rod 17, and interposed between the crank arms 14 and 16 is the upper end of a connecting rod 18, as shown in Fig. 3, said connecting rods 17 and 18 providing means by which two rectangular frames are suspended in overhanging suspended relation to the tanks 85 1 and 2, which frames afford supports for 90 carriers of the material to be pickled.

Said supporting frames, as herein shown, are composed of parallel longitudinally extending side members, each formed of two rigidly attached channel irons 19, and transverse channel irons 20 connecting said side members adjacent their ends, spacers 21 being received between and riveted to the confronting faces of the companion channel irons 19. 100

- Trunnions (not shown) are provided between the channel irons 19 adjacent the ends thereof, the trunnions of the outer side members of the frame being received by the lower ends of the connecting rods 17, and the trunnions of the inner side members of the frame (the side members superposed above the confronting sides of the tanks) being received by the lower ends of the connecting rods 18.
- 10 An electric motor 23 is mounted upon the foundation 3 rearward of the gear box 4 and has the drive shaft thereof suitably coupled to a stub shaft 24 of the gear box. As will be understood from the drawings, operation 15 of the motor 23 results in rotation of each of the four shafts 12, the two shafts 12 at one end of the tank being rotated in a clockwise manner, as indicated by the arrow in Fig. 2, through the intermediacy of the gear box 4, 20 while the shafts 12 at the opposite end of the tanks are rotated in a counterclockwise manner by means of the drive shaft 6 and appropriate gearing contained within the gear box 5.
- 25 Obviously, rotation of the shafts and the thereby carried crank arms at the opposite ends of the tanks in reverse directions results in the frames carried by the connecting rods 17 and 18 being vertically reciprocated 30 with each revolution of the crank arms.
- 35 A guide plate 25 is permanently fixed to the inner side walls of the foundations 3 adjacent the ends of the two frames and each of said guides 25 has its two vertical side edges abutted by plates 26 permanently attached to the end channels 20 of each frame. Said plates are designed for vertical movement with respect to said guide 25 during 40 reciprocating movements of the frames in the operation of the apparatus, the same providing means for substantially true vertical reciprocation of the frames. Additionally, the guide mechanism described affords means for maintaining the frame rigid with respect 45 to the operating mechanism when the carrier is being placed on the frame or when being removed therefrom, as will hereinafter be described.
- 50 Each of said frames has located between its ends spaced transverse I-beams 27 that have their opposite ends attached to the side members of the frame by means of angles 28 attached to the side members by means of rivets. A saddle-like member 29 is bolted 55 to each of said transverse beams 27 at an appropriate distance between the ends thereof, the saddle members being designed to serve as supports for the carriers of the material to be pickled.
- 60 Each of said carriers is composed of a horizontal bar 30, the ends of which rest in the depressions of the saddle members 29. The bar 30 is provided with depending members 31 and 32, the member 31 being pivoted 65 at 33 to the bar 30 and being of substantially

U-shape. A horizontal member 34 is pivoted at 35 to the depending member 32 and has its opposite end free and formed to rest upon the closed bottom of the U-shaped member 31. The pivoted end of the member 32 is shouldered, as shown at 36, and engages a corresponding shoulder formed in the bottom of the member 34 to rigidly hold the member in position by the weight of the coiled metal strips 37, as shown in Fig. 3.

70 The upper face of the horizontal member 34 is preferably formed with a plurality of horizontally aligned drilled holes adapted to have snugly received therein the lower ends of spacing pins or fingers 38. Said fingers 80 are designed as separators for the coiled strips, allowing the picking of strips of varying widths without longitudinal shifting thereof, as shown in Fig. 2. A detachable horizontal keeper 39 has its opposite ends attached, respectively, to the depending members 85 31 and 32 and has a plurality of horizontally aligned drilled holes in its under face adapted to receive the upper ends of the spacing fingers 38.

90 The bar 30 is provided with eyes or loops 40 for engagement with a lifting crane, as will be hereinafter explained.

95 As shown in Fig. 3, a cradle 41 is stationarily suspended within each of the tanks 1 and 2, said cradle having spaced longitudinal bars 42, which latter are disposed in the arc of a circle. Clamping brackets or clips 43 are secured to the top edges of the sides of the tanks, said brackets having attached thereto the upper ends of downwardly and convergently related rods 44, which rods have their lower ends secured to the cradle 41 for stationarily supporting the latter in the 100 pickling tank.

105 In operation, it will be seen that, in order to load the coils 37 on the carrier, the carrier is first disconnected from the apparatus. Then the free end of the horizontal member 34 is raised and the pivoted member 31 is 110 swung outwardly, or to the left of Fig. 2, which enables the coiled strips 37 to be positioned onto the member 34. In other words, the coiled strips are threaded on said member 34. After such positioning of the coils 115 upon the member, the latter is moved to the position shown in Fig. 2, in which position it engages the member 31. The spacing pins or fingers 38 then have their lower end portions introduced in appropriate holes in the member 34 to suitably separate the coils, as hereinbefore explained. The keeper 39 is then positioned over said fingers so as to embrace the upper end portions thereof, the opposite ends of said keeper being attached in any appropriate manner, as by means of pins or bolts, to the depending members 31 and 32, respectively.

120 A lifting crane is then connected to the carrier by means of the eyes 40 and the same 125

is carried to a position wherein its bar 30 seats in alined saddle members 29 of the supporting frames.

With the carriers of the companion frames 5 loaded and positioned as above described, power is applied to the operating mechanism by means of the motor 23. This power is transmitted to the shafts 12; crank arms 13, 14 and 16; connecting rods 17 and 18, in a 10 manner hereinbefore described so as to impart vertical reciprocal movements to the frames and the thereby carried loads, resulting in the coils being alternately plunged upwardly and downwardly in the pickling fluid 15 of the bath.

It will be noted that the two supporting frames have alternate vertical movements—that is, the frame of one tank travels in a downward direction while the frame of the 20 other tank travels in an upward direction, and vice versa. Such alternate movements of the reciprocating frames tends to provide a balanced apparatus and results in a minimum of power consumption being required 25 for operation.

Referring particularly to Fig. 3 of the drawings, it will be seen that the limit of the down stroke of the carrier is such that the 30 bottom portions of the coils come in contact with or are impacted against the cradle 41 and the weight of said coil is thereby transferred from the carrier to the cradle, resulting in the spreading or opening up of the 35 convolutions of the coils of the upper portion of the coils. On the up stroke of the carrier, the bar 34 carries the entire weight of the coils, closing the convolutions of the upper portion of the coils and spreading the convolutions of the lower portion by reason 40 of their own weight. This opening or closing of the convolutions of the coils, shown more or less diagrammatically in Fig. 3, enables the pickling fluid to have free and complete access to the entire surface of the coiled strips. 45

It will be understood that, while I have specifically shown and described my invention as being intended for the purpose of pickling coiled metal strips or wire, the apparatus may be readily and conveniently converted so as to accommodate steel sheets, forgings, and the like. In this event, the stationary cradle 41 is preferably removed from the tanks and any desired form of rack or basket 50 substituted for the carrier herein shown and described. For this reason, it will be understood that changes and modifications may be resorted to within the scope of the following 55 claims.

co What is claimed is—

1. A pickling apparatus of the character described comprising a pair of spaced pickling tanks, a stationary cradle mounted in each of said tanks, a vertically reciprocating frame 65 permanently disposed above each of said

tanks and comprising a pair of longitudinal members spaced apart by a pair of transverse members suitably to the reception of an article carrier, a removable article carrier supported by each of said frames, and power means connected to said frames whereby to alternately reciprocate the frames and thereby the articles carried by the latter into and out of engagement with said cradle. 70

2. In a pickling apparatus, a pickling tank a stationary cradle carried by and suspended within said tank, a frame permanently located and movably supported above said tank and comprising a pair of longitudinal members spaced apart by a pair of transverse members suitably to the reception of an article carrier, an article carrier supported by said frame, power means, a rotary shaft connected to said power means, and means connecting said shaft and frame whereby operation of the power means imparts a vertical reciprocatory motion to the frame and the thereby supported article carrier. 75 80 85

3. In a pickling apparatus, a pickling tank having an open top, a stationary cradle supported by and disposed within said tank, a transversely disposed crank shaft supported adjacent each end of the tank, a frame permanently supported by said crank shaft in spaced relation to the upper edge of the tank and comprising a pair of longitudinal members spaced apart by a pair of transverse members suitably to the reception of an article carrier, an article supporting member carried by the frame and disposed within the tank, power means, and means connecting each of said crank shafts for imparting opposite rotative movement to the latter upon operation of the power means whereby to vertically reciprocate said frame, the articles supported within the tank being impacted against the stationary cradle during the reciprocatory movement of the frame to separate said articles. 90 95 100 105 110

4. In a pickling apparatus, a pickling tank a stationary cradle carried by and disposed within said tank, a vertically reciprocating frame mounted above said tank, a removable coil holder mounted within said frame, adjustable spacer bars mounted within said coil holder whereby to accommodate coils of varying widths, and power means for reciprocating said frame to cause said coils to be impacted against the cradle for separating 115 the convolutions of said coils. 120

5. In a pickling apparatus, a pickling tank, a stationary cradle carried by and disposed within said tank, a vertically reciprocating frame mounted above said tank, a removable coil holder mounted within said frame, adjustable spacer means mounted within said coil holder whereby to accommodate coils of varying widths, and power means for reciprocating said frame to cause said coils to 125 130 135

and arranged to size, a pickling tank, a stationary cradle carried by and disposed within said tank, a vertically reciprocating frame mounted above said tank, a removable article holder mounted within said frame, adjustable spacer bars mounted within said article holder whereby to accommodate articles of varying widths, and power means for reciprocating said frame to cause said articles to be impacted against the cradle for moving the articles upon said holder.

6. In a pickling apparatus, a pickling tank, a stationary cradle carried by and disposed within said tank, a vertically reciprocating frame mounted above said tank, a removable article holder mounted within said frame, adjustable spacer bars mounted within said article holder whereby to accommodate articles of varying widths, and power means for reciprocating said frame to cause said articles to be impacted against the cradle for moving the articles upon said holder.

7. A pickling apparatus of the character described comprising a pair of spaced pickling tanks, a vertically reciprocating frame permanently disposed above each of said tanks and comprising a pair of longitudinal members spaced apart by a pair of transverse members suitably to the reception of an article carrier, a removable article carrier supported by each of said frames, means in the tank for engaging the articles to cause same to completely engage the pickling fluid, and power means including parts disposed between said tanks and connected to said frames whereby to alternately reciprocate the frames and thereby the articles.

8. In a pickling apparatus, a pickling tank, a transversely disposed crank shaft supported adjacent each end of the tank, a frame supported by said crank shafts in spaced relation above said tank, power means, means interposed between said crank shafts for imparting opposite rotative movements to the latter upon operation of the power means whereby to vertically reciprocate said frame, and a carrier adapted to be removably mounted on said frame.

9. A pickling apparatus of the character described comprising companion pickling tanks, drive shafts located at the opposite ends of said tanks, crank arms mounted on said shafts, connecting rods pivotally connected to said crank arms and supporting a frame in suspended relation above each of said tanks, each of said frames comprising a pair of longitudinal members spaced apart by a pair of transverse members suitably to the reception of an article carrier.

10. A pickling apparatus of the character described, comprising a pair of spaced pickling tanks, transversely disposed crank shafts adjacent the ends of said tanks, a gear box interposed between the transverse shafts at each end of said tanks, a horizontal drive shaft connecting said gear boxes, frames supported by said crank shafts, one over each tank, said frames being adapted to support an article carrier thereon, and means for rotating said crank shafts to impart alternate elevating and lowering movements to said frames.

65 In testimony whereof, I affix my signature.
STEPHEN L. WILLIAMS.
